LOOSE-LEAF BINDER

Max W. Federbush, New York, N. Y.

Application September 22, 1950, Serial No. 186,138

1 Claim. (Cl. 129—8)

1 This invention relates to loose leaf binders.

It is an object of the present invention to provide in a loose leaf binder, cooperating coupling parts which are simple to construct and assemble and formed of a minimum number of pieces, and wherein ample ball contact is had with the interfitting post of one of the parts.

Other objects of the present invention are to provide a loose leaf binder assembly which is easily handled, the cover parts easily placed about the loose sheets and wherein the disengagement of the binder parts is easily effected by a single pull of a ring and the release of a sleeve from a post on the other cover part.

For other objects and for a better understanding of the invention, reference may be had to the following detailed description taken in connection with the accompanying drawing, in which

Fig. 1 is a perspective view of the loose leaf binder showing the pull member being lifted in order to separate the binder parts and to make free the loose leaf sheets.

Fig. 2 is a perspective view of the binder parts separated and illustrating the manner of connecting or disconnecting the loose leaf sheets from the other binder part.

Fig. 3 is an exploded and perspective view of the securing sleeve assembly and of the post over which this sleeve assembly is fitted.

Fig. 4 is an enlarged vertical sectional view taken on line 4—4 of Fig. 1.

Fig. 5 is a fragmentary and still enlarged sectional view showing the spring compressed and the parts pulled to release the ball elements.

Fig. 6 is an enlarged view showing the engagement of the ball elements with the stud pin to secure the cover parts in their locked positions.

Referring now to the figures, 10 and 11 represent respectively binder cover parts. The part 10 has a rigid upstanding flange 12 and a plurality of pins 13 extending upwardly and adjacent to the flange 12. Loose leaf sheets 14 having holes 15 are disposed on the pins 13. The sheets may have five holes extending along one edge of the same. A narrow plate 16 having projections 17 is fitted through the sheets 14 and the assembly of the sheets and plate can be fixed, as shown in Fig. 2, so that the projections 17 extend through other holes 15. The plate 16 has a large hole 18 intermediate its length for receiving a fastening sleeve assembly 19. The sheets may similarly be provided large enough to accommodate the sleeve assembly 19.

The binder cover part 11 has a rigid flange 21 that carries the sleeve assembly 19. With the

2 cover flange 22 placed against the flange 12 of the cover part 10, the sleeve assembly will be aligned with the opening 18 in the narrow plate 16 and adapted to be secured to the intermediate pin 13' on the binder part 10.

The pins 13 and 13' are made secured to the binder cover part 10 by peening over the securing end of the pin, in the manner as shown at 23, to bring the binder part against flange 24 on the pin. With the binder part being reinforced with a metal sheet, the pins 13 and 13' will be held rigidly and normal to the face thereof. The pins 17 are similarly secured to the narrow plate 16, as indicated at 25.

15 The sleeve assembly 19 comprises an outer sleeve 27 which has a tapered internal opening 28, as shown in exaggerated form in Fig. 6. The upper end of the sleeve 27 has a flange 29. The upper end of the sleeve is made secure upon the flange 21 of the cover part 11 by a slightly tapered plug part 31 having an axial opening extending therethrough and which is tight fitted into the tapered opening 28 and extended through a hole in the flange part 21. This part 31 has a hole 20 therein through which is slidably an operating member 32 which has an enlarged hollow portion 33 for receiving the pin 13'. A shoulder 34 is provided against which a spring 35 reacts to normally urge the operating member 32 forwardly so that its finger ring 36 engages the outer face 21 of the plug part 31. A finger can be extended through the ring to lift the operating member 32 against the action of spring 35 and to a position as shown in Fig. 5. The spring 35 will be compressed.

30 35 The lower end of the hollow portion 33 has a plurality of circumferentially spaced holes 37 in which are retained small locking ball elements 38. These ball elements ride along the surface 28 and will engage with the surface of the projection or pin 13' to retain and lock the same against outward displacement from the hollow portion 33. With an outward pull of the projection 13', the balls will be rolled into tight gripping relationship therewith. By this means, the locking action of the pin with the sleeve assembly 19 is effected. To release the pin 13' and the balls 38 from their engagement therewith, the operating member 32 and the balls are drawn inwardly 40 so that the balls may be made free.

45 The matter of removing sheets 14 from the book can be readily effected by a simple lifting of the ring 36, in the manner as shown in Fig. 1, and removing certain of the sheets with the narrow plate 16, in the manner as shown in Fig. 2. Com-

plete control is kept of all of the sheets and the sheet in particular which it is desired to have removed, can be readily removed without control being lost of any of the sheets. The sheets at all times will be kept on pins, whether the pins are in the part 10 or in the plate 16.

It will be apparent that the assembly of the parts of the latch sleeve assembly 19 upon the binder cover part 10 is effected in an easy manner and by a simple tight fitting of the plug 31 into the end of the sleeve 27 and over the flange 29. The operating member 32 with the spring 35 and the balls 38 will have been assembled and extended through the opening in the plug 31 prior to the fixing of the plug in the end of the sleeve 27.

While various changes may be made in the detail construction, it shall be understood that such changes shall be within the spirit and scope of the present invention as defined by the appended claim.

What is claimed is:

A loose leaf binder construction comprising binder cover parts having overlapping flanges, one of said parts having upstanding pin projections adapted to enter respectively openings in the loose leaves, a narrow plate having pin projections extendable in the opposite direction and adapted to enter respectively other openings in the loose leaves, said narrow plate having a large hole midway its length thereof, the other binder cover part having an inwardly extending flange adapted to overlie the narrow plate when the cover parts are brought together, a sleeve fastener, assembly rigidly fixed to the flange of the other binder cover part and adapted to extend through the large hole in the narrow plate and over one of the pins projecting upwardly from the one binder cover part, said sleeve assembly comprising a sleeve having an internal tapered opening and a top flange adapted for engagement with the underside of the binder cover part flange, a slightly tapered plug extending through

the inwardly extending flange of the other binding cover part and having a flange overlying the upper side of the other binder cover part flange and an axial opening extending therethrough, said plug tightly fitted in the flanged end of the sleeve and the flanges of the sleeve and plug cooperating with the other cover binder part flange to fix the sleeve fastener assembly to the other binder cover part flange, an operating member in said sleeve, and slidably through said plug axial opening said operating member having a hollow sleeve portion adapted to receive one of the pins of the one binder cover part and a shoulder portion, a plurality of circumferentially spaced openings in the lower end of said hollow sleeve portion, gripping balls lying respectively in the circumferentially spaced holes and operable over the tapered internal surface of the sleeve, a spring surrounding the operating member and engaging the slightly tapered plug and the shoulder portion on the operating member whereby to normally urge the operating member outwardly of the sleeve and the gripping balls in tight engagement with the internally tapered opening of the sleeve, a pull ring fixed on the outer end of the operating member and extending laterally thereof whereby to act, against the flange of the slightly tapered plug to serve as a stop to limit the outward movement of the operating member and to confine the gripping balls within the end of said sleeve.

MAX W. FEDERBUSH.
